METHOD AND MEANS FOR USE IN
MAKING SHOESFred N. La Chapelle, Beverly, Mass., assignor to
United Shoe Machinery Corporation, Paterson,
N. J., a corporation of New Jersey

Application December 21, 1933, Serial No. 703,443

40 Claims. (Cl. 12—14)

This invention relates to the manufacture of shoes and more particularly to the shaping of shoe uppers over forms or lasts and the fastening of the uppers to insoles or other shoe bottom parts. The invention is herein illustrated by reference to the lasting of the toe end of a welt shoe, including the fastening of the marginal portion of the upper in lasted position over the margin or feather of an insole and against a lip on the insole by the use of a binder extending around the toe. It is to be understood, however, that the invention is not limited to the manufacture of shoes of the welt type or to the lasting of the toe ends of shoes, and also that in some novel aspects it is not limited to the use of upper-holding members or fastenings in the form of binders adapted to extend around the ends of shoes. In view of the general applicability of the invention to the manufacture of shoes of different kinds, the term "sole" is commonly used hereinafter in a generic sense to refer to the insole or other shoe bottom part to which the marginal portion of the upper is fastened.

In one aspect, the invention provides a novel method in accordance with which an upper holding fastening is forced over the marginal portion of an upper on the margin of a sole in a path substantially parallel to the general plane of the sole and is so engaged in that operation as to deflect a portion of it into the upper and the sole in a direction transverse to the plane of the sole. Preferably, as shown, the portion of the fastening that is thus deflected into the upper and the sole is curved during its deflection to assist in anchoring the fastening to the shoe. For use on an end portion of a shoe the upper-holding fastening, as illustrated, consists of a binder adapted to extend around the end of the shoe and having thereon a plurality of projections that lie initially in a plane, and as the binder is forced inwardly over the marginal portion of the upper its several projections are deflected into the upper and the sole in the manner above described. If the sole, as illustrated, has thereon an upstanding lip or shoulder against which a portion of the upper lies in lasted position, the upper-holding member or binder is forced inwardly toward said lip or shoulder, and as herein shown its projections are so deflected that they enter the upper and the sole in locations nearer the edge of the sole than the lip or shoulder. Preferably, as further illustrated, the projections on the binder are deflected in curved paths leading reversely outward toward the edge of the sole, which, in the case of a welt shoe, facilitates removal of the binder by pulling it in an outward direction toward the edge of the

shoe bottom after a welt has been fastened to the shoe.

The invention further provides, in a machine for shaping shoe uppers, a novel organization of means for operating on shoes in accordance with the above described method, comprising means movable in a path substantially parallel to the general plane of a sole to force an upper-holding fastening over the marginal portion of the upper, and means for deflecting a portion of the fastening into the upper and the sole in a direction transverse to the plane of the sole. As herein shown, there is associated with the toe-embracing wipers of a lasting machine means for forcing inwardly over the marginal portion of the upper a toe binder formed as above described, and the wipers are so constructed as to engage the projections on the binder and deflect them into the upper and the sole as the binder is thus forced inwardly.

The novel method and novel mechanical features of the invention will now be more particularly described by reference to the accompanying drawings and pointed out in the claims.

In the drawings,

Fig. 1 is a view in front elevation of a portion of a bed-lasting machine adapted for use in the practice of the novel method and in which features of the invention are embodied;

Fig. 2 is a plan view of a portion of the structure shown in Fig. 1;

Fig. 3 is a vertical central section longitudinally of the shoe of a portion of the machine, showing the parts in the positions that they occupy after the toe binder has been forced into upper-holding position;

Fig. 4 is a section on the line IV—IV of Fig. 2;

Fig. 5 is a perspective view of the lasted toe end of the shoe; and

Fig. 6 is a sectional view of the toe end of the shoe as it appears after a welt has been fastened to the shoe and before the toe binder is removed.

The invention is herein illustrated by reference to a bed-lasting machine of a well-known commercial type, features of which are disclosed in various prior United States Letters Patent, including especially Letters Patent No. 1,018,477, granted on February 27, 1912 upon an application of Matthias Brock and disclosing the main characteristic features of the general organization of the machine. Only such parts of the machine, therefore, as it is necessary to refer to for an understanding of the invention will be herein-after mentioned.

The shoe and last are supported at the heel end on a jack 10 with the toe end of the shoe resting upon a toe rest 12, and in the lasting operation the toe end of the shoe is pressed down 10.

upon the toe rest by a holddown 14 carried by an arm 16. The toe-lasting means as a whole is supported on a slide 18 which may be moved upwardly and downwardly by the operator, 5 through use of a treadle 20, to wipe the toe end portion of the upper heightwise of the last end to press the marginal portion of the toe end of the upper down upon a sole on the last. Included in the toe-lasting mechanism is a toe wiper head 22 on which are movably supported toe-embracing wipers 24. In the construction herein shown each of the wipers 24 comprises two plates 26 and 28 (Figs. 3 and 4) which are spaced from each other heightwise of the shoe to provide an opening 10 between them in which is mounted a binder-applying member or plate 30 hereinafter more particularly described. As herein illustrated also the wipers 24 are supported directly upon the wiper head 22, instead of upon movable wiper carriers as heretofore, and both plates 26 and 28 of each wiper have therein curved slots 32 and 34 (Fig. 2) in which lie rolls 36 and 38 to guide the wiper in its advancing and closing movements, these rolls being mounted on pins 40 and 25 42 which are fastened to a cover plate 44 over the wipers. The wipers are advanced and closed through links 46 pivotally connected to pins 48 which extend through the plates 26 and 28, the links being connected to a cross-bar 50 which 30 is fast on a rod or plunger 52 operated by a hand lever 54 (Fig. 1) as heretofore in machines of the illustrated type. As the wipers are advanced and closed, after the wiping of the upper heightwise of the toe, they wipe its marginal portion inwardly over the margin of the sole *a*, and if the sole is provided with an upstanding lip *b* characteristic of welt shoe work, as illustrated, they 35 wipe a portion of the upper against the upstanding lip. It will be understood that in some kinds of work the sole will be provided with a shoulder, 40 instead of a lip, against which the upper is wiped.

To fasten the marginal portion of the upper in lasted position around the toe end of the shoe bottom there is utilized, as herein illustrated, an upper-holding member or binder *c* which may be 45 formed, for example, of sheet metal and has thereon a plurality of pointed projections *d* arranged to lie initially in the same plane. The binder *c* is of such length as to extend around the tie end portion of the shoe bottom, and it may 50 be so formed as to have somewhat of an initial curvature as illustrated in Fig. 2. Prior to the lasteting of the toe this binder is inserted endwise in the opening between the wiper plates 26 and 28 in front of the binder-applying plates 30 and 55 near the edges of the wipers, as also illustrated in Fig. 2. When the binder is in that position its projections *d* are all pointed inwardly toward the shoe along the plane of the wipers. When the wipers are operated as described to wipe the upper inwardly over the margin of the sole, the binder may be carried bodily forward more or less by the contact of the wipers therewith. After the wipers have completed their wiping 60 movements and while they are holding the marginal portion of the upper in lasted position, the binder is applied to the shoe by movements of the plates 30 the forward edges of which are curved in general similarity to the curvature of the wiper edges. In thus applying the binder the plates 30, 65 operated as hereinabove described, move in a path substantially parallel to the plane of the sole to advance the binder lengthwise of the shoe and to bend it around the toe toward the lip *b* of the sole. In the path of the projections *d* of the bind-

er, as the latter is moved forwardly and bent around the toe, are downturned lips 56 on the wiper plates 26 which have curved deflecting faces 58 (Fig. 4) arranged in the plane of the opening between the plates 26 and 28 to engage the projections *d* and to deflect them into the upper and the sole toward the bottom face of the last, the lips 56 being spaced from the edges of the lower wiper plates 28 sufficiently to permit this action as well as to permit the wipers later 10 to be withdrawn from the binder by lifting them. By reference to Fig. 3 it will be seen that the projections *d* enter the upper and the sole in locations nearer the edge of the sole than the lip *b* and are deflected in curved paths leading 15 reversely outward toward the edge of the sole. The binder is thus anchored securely in position to hold the upper pressed closely into the angle between the margin or feather of the sole and the lip *b* all around the toe preparatory to the welt-sewing operation.

The binder-applying plates 30 are guided in their movements by the same rolls 36 and 38 that guide the wipers, the plates having for this purpose curved slots 32 and 34 through which the 25 rolls extend. These slots are so formed and arranged that by the operation of the plates 30 the binder is forced into holding relation to the upper at the extreme end of the toe and its projections 30 *d* are deflected into the upper and the sole in that location a little before the projections on the portions of the binder at the sides of the toe are deflected into the shoe. This avoids such difficulties as would be encountered if the projections along the sides of the toe should start to 35 enter the shoe prior to the substantial completion of the movement of the binder as a whole lengthwise of the shoe.

For imparting the operative movements to the binder-applying plates 30 there is provided a rod 40 or plunger 64 slidably movable lengthwise in a member 66 on the wiper head 22 and provided at its forward end with a cross-bar 68 which carries pins 70 extending downwardly into slots 72 formed in the plates 30, these slots being arranged to permit the plates to swing relatively to the pins in their closing movements laterally of the shoe. In operating the plates 30 the pins 70 move along slots 72 provided in the cover plate 44. The rod 64 is operated by a hand lever 76 50 pivotally connected by a pin 78 to a block 80 which is fast on the rod, the lever being pivoted at 82 (Fig. 2) on a link 84 which is pivoted at 86 on the wiper head. The pins 48 which connect the links 46 to the wipers extend through 55 the binder-applying plates 30, and in order to permit the required movements of the wipers before the plates 30 are operated there are provided in these plates slots 88 affording sufficient room for the movements of the pins in the operation of the wipers.

In view of the foregoing description the manner in which the novel method is carried out by use of the illustrated machine need be only briefly summarized. The binder, formed as described, is first inserted lengthwise in the space between the upper and lower wiper plates 26 and 28, and thereafter the wipers are used in the customary manner to wipe the upper heightwise of the toe and to wipe its marginal portion 70 inwardly over the sole into lasted position. It will be understood that the lips 56 on the wiper plates 26 serve as the upwiping means and also in part as means to wipe the upper inwardly over the sole, the lips being assisted in the lat- 75

ter operation by the plates 28, as will be evident by reference to Fig. 3. While the wipers are holding the upper in lasted position the binder-applying plates 39 are operated to advance the binder c lengthwise of the shoe and to bend it inwardly around the toe into holding relation to the marginal portion of the upper, the projections d on the binder being deflected into the upper and the sole by the deflecting faces 58 on the wiper plates 26, first at the end of the toe and thereafter at the sides of the toe. After the binder has thus been applied the wipers are lifted by the treadle 20 to clear the binder from the opening between the edges of the plates 28 and the lips 56 and are then withdrawn to their starting positions. While the binder remains on the shoe a welt e (Fig. 6) may be applied in the customary manner. Thereafter the binder may be removed from the shoe by pulling it outwardly toward the edge of the shoe bottom under the welt. The fact that the projections d of the binder are curved reversely outward toward the edge of the sole facilitates such removal of the binder, since they can be withdrawn more readily by such an outward pull on the binder than if they were curved in some different relation to the edge of the sole.

While the binder is herein shown as provided with a plurality of projections d arranged to penetrate the shoe at each of the opposite sides of the toe, and also a plurality of projections that penetrate the shoe at the end of the toe, it will be understood that the number of the projections on the binder and their locations relatively to the shoe may be varied within the scope of the invention. It will also be recognized that the application of the binder to the shoe and the deflection of its projections into the upper and the sole in the manner disclosed is not dependent upon the presence of an upstanding lip or shoulder on the sole, and accordingly that the invention may be utilized in the manufacture of shoes in which the sole has no such lip or shoulder. It is also to be understood that the upper-holding member or fastening utilized need not be in the form of a binder adapted to extend around an end of a shoe.

Having described the invention, what I claim as new and desire to secure by Letters Patent of the United States is:

1. That improvement in methods of making shoes which consists in laying the marginal portion of an upper upon the margin of a sole, forcing an upper-holding fastening over the marginal portion of the upper in a path substantially parallel to the general plane of the sole, and by engagement with the fastening as it is thus forced over the upper deflecting a portion of it into the upper and the sole in a direction transverse to the plane of the sole.

2. That improvement in methods of making shoes which consists in laying the marginal portion of an upper upon the margin of a sole, forcing an upper-holding fastening over the marginal portion of the upper in a path substantially parallel to the general plane of the sole, and by engagement with the fastening exteriorly of the shoe as it is thus forced over the upper curving a portion of it progressively in a direction transverse to the plane of the sole to cause it to enter the upper and the sole.

3. That improvement in methods of making shoes which consists in laying the marginal portion of an upper upon the margin of a sole, forcing an upper-holding fastening over the marginal

portion of the upper in a path leading inwardly from the edge of the sole and substantially parallel to the general plane of the sole, and by engagement with the fastening as it is thus forced inwardly over the upper deflecting a portion of it into the upper and the sole in a curved path leading reversely outward toward the edge of the sole.

4. That improvement in methods of making shoes which consists in laying the marginal portion of an upper inwardly over a sole on a last, forcing an upper-holding fastening inwardly along the marginal portion of the upper in a path substantially parallel to the bottom of the last, and by engagement with the fastening as it is thus forced inwardly deflecting a portion of it into the upper and the sole in a direction toward the bottom of the last.

5. That improvement in methods of making shoes which consists in laying the marginal portion of an upper inwardly over the margin of a sole and against an upstanding lip or shoulder on the sole, forcing an upper-holding fastening inwardly toward said lip or shoulder, and by engagement with the fastening exteriorly of the shoe as it is thus forced inwardly deflecting a portion of it into the upper and the sole in a direction transverse to the path of inward movement of the fastening.

6. That improvement in methods of making shoes which consists in laying the marginal portion of an upper inwardly over the margin of a sole on a last and against an upstanding lip or shoulder on the sole, forcing an upper-holding fastening inwardly toward said lip or shoulder in a path substantially parallel to the bottom of the last, and by engagement with the fastening exteriorly of the shoe as it is thus forced inwardly deflecting a portion of it in a direction toward the bottom of the last to cause it to penetrate the upper and the sole in a location nearer the edge of the sole than said lip or shoulder.

7. That improvement in methods of making shoes which consists in laying the marginal portion of an upper inwardly over the margin of a sole and against an upstanding lip or shoulder on the sole, forcing an upper-holding fastening inwardly from the edge of the sole toward said lip or shoulder over the marginal portion of the upper, and by engagement with the fastening as it is thus forced inwardly deflecting a portion of it into the upper and the sole in a location nearer the edge of the sole than said lip or shoulder and in a curved path leading reversely outward toward the edge of the sole.

8. That improvement in methods of making shoes which consists in laying the marginal portion of an upper upon the margin of a sole around an end of a shoe, forcing into holding relation to the marginal portion of the upper around the end portion of the shoe an upper-holding member having projections thereon, and by engagement with said projections as said member is thus forced into upper-holding position deflecting them into the upper and the sole in directions transverse to the path of movement of said member.

9. That improvement in methods of making shoes which consists in laying the marginal portion of an upper inwardly over the margin of a sole on a last around an end of the shoe bottom, forcing inwardly over the marginal portion of the upper around the end portion of the shoe bottom in a path substantially parallel to the bottom of the last an upper-holding member hav-

ing projections thereon, and by engagement with said projections exteriorly of the shoe as the upper-holding member is thus forced inwardly curving them in directions toward the bottom 5 of the last to cause them to enter the upper and the sole.

10. That improvement in methods of making shoes which consists in laying the marginal portion of an upper upon the margin of a sole around an end of a shoe, forcing inwardly from the edge of the sole over the marginal portion of the upper an upper-holding member formed to extend around the end portion of the shoe and having projections thereon, and by engagement 15 with said projections as said member is thus forced inwardly over the upper deflecting them into the upper and the sole in curved paths leading reversely outward toward the edge of the sole.

11. That improvement in methods of making 20 shoes which consists in laying the marginal portion of an upper inwardly over the margin of a sole and against an upstanding lip or shoulder on the sole around an end of the shoe bottom, forcing inwardly toward said lip or shoulder 25 around the end of the shoe bottom an upper-holding member having projections thereon, and by engagement with said projections as the upper-holding member is thus forced inwardly deflecting them into the upper and the sole in directions 30 transverse to the path of inward movement of the member.

12. That improvement in methods of making 35 shoes which consists in working the marginal portion of an upper around an end of a last into lasted position over the margin of a sole on the last and against an upstanding lip or shoulder on the sole, forcing inwardly toward said lip or shoulder in a path substantially parallel to the bottom of the last an upper-holding binder 40 formed to extend around the end of the shoe bottom and having projections thereon, and by engagement with said projections exteriorly of the shoe as the binder is thus forced inwardly deflecting them toward the bottom of the last to cause them to penetrate the upper and the sole 45 in locations nearer the edge of the sole than said lip or shoulder.

13. That improvement in methods of making 50 shoes which consists in working the marginal portion of an upper around an end of a last into lasted position over the margin of a sole on the last and against an upstanding lip or shoulder on the sole, forcing inwardly from the edge of the sole over the marginal portion of the upper 55 toward said lip or shoulder an upper-holding binder formed to extend around the end portion of the shoe bottom and having projections thereon, and by engagement with said projections as the binder is thus forced inwardly deflecting them into the upper and the sole in curved paths leading 60 reversely outward toward the edge of the sole.

14. That improvement in methods of fastening 65 end portions of shoe uppers in lasted position which consists in providing an upper-holding binder formed to extend around an end of a shoe and having thereon a plurality of projections lying substantially in a plane, forcing said binder inwardly into upper-holding position around an end of a shoe, and by engagement with said projections as the binder is thus forced inwardly deflecting them out of said plane through the upper 70 and into a sole.

15. That improvement in methods of fastening 75 end portions of shoe uppers in lasted position which consists in providing an upper-holding

binder formed to extend around an end of the bottom of a shoe and having thereon a plurality of projections lying substantially in a plane, forcing said binder inwardly over the bottom of a shoe on a last into upper-holding position around an end of the shoe bottom, and by engagement with said projections as the binder is thus forced inwardly deflecting them out of said plane into the upper and the sole in directions toward the bottom of the last.

16. That improvement in methods of fastening 10 end portions of shoe uppers in lasted position which consists in providing an upper-holding binder formed to extend around an end of the bottom of a shoe and having thereon a plurality of projections lying substantially in a plane and arranged to enter an upper in a plurality of different locations at each of the opposite sides of the end of the shoe bottom, forcing said binder inwardly over the bottom of a shoe on a last 15 into upper-holding position around an end of the shoe bottom, and by engagement with said projections exteriorly of the shoe while thus forcing the binder inwardly deflecting them in curved paths into the upper and the sole toward the bottom face of the last.

17. In a machine for shaping shoe uppers, 20 means for laying the marginal portion of an upper over the margin of a sole, means movable in a path substantially parallel to the general plane 25 of the sole to force an upper-holding fastening over said marginal portion of the upper, and deflecting means constructed and arranged to engage a portion of the fastening as it is thus forced over the upper and to deflect it into the upper 30 and the sole in a direction transverse to the plane of the sole.

18. In a machine for shaping shoe uppers, 35 means for laying the marginal portion of an upper over the margin of a sole, a device movable in a path substantially parallel to the general plane 40 of the sole to force an upper-holding fastening over said marginal portion of the upper, and deflecting means constructed and arranged to engage a portion of the fastening as it is thus forced over the upper end to curve it progressively 45 in a direction transverse to the plane of the sole to cause it to enter the upper and the sole.

19. In a machine for shaping shoe uppers, 50 means for laying the marginal portion of an upper over the margin of a sole, a device movable in a path substantially parallel to the general plane of the sole to force an upper-holding fastening in a direction inwardly from the edge of the sole over said marginal portion of the upper, 55 and means constructed and arranged to engage a portion of the fastening as it is thus forced inwardly over the upper and to deflect it into the upper and the sole in a curved path leading reversely outward toward the edge of the sole.

20. In a machine for shaping uppers over lasts, 60 means for laying the marginal portion of an upper inwardly over a sole on a last, a device movable in a direction substantially parallel to the bottom of the last to force an upper-holding fastening 65 inwardly over the marginal portion of the upper, and deflecting means constructed and arranged to engage a portion of the fastening as it is thus forced inwardly and to deflect it into the upper and the sole in a direction toward the bottom of the last.

21. In a machine for shaping shoe uppers, an 70 overlaying device for laying the marginal portion of an upper over the margin of a sole, and means movable along said overlaying device in a path 75

substantially parallel to the general plane of the sole to force an upper-holding fastening over said marginal portion of the upper, said overlaying device having thereon a deflecting face arranged 5 to engage a portion of the fastening as it is thus forced over the upper and to deflect it into the upper and the sole in a direction transverse to the plane of the sole.

22. In a machine for shaping shoe uppers, wiping means movable in a path substantially parallel to the general plane of a sole to wipe the marginal portion of an upper inwardly over the sole, and a device movable in a path substantially parallel to the path of movement of said wiping means to force an upper-holding fastening inwardly over the marginal portion of the upper, said wiping means having thereon a deflecting face arranged to engage a portion of the fastening as it is thus forced inwardly over the upper and to deflect it into the upper and the sole in a direction transverse to the plane of the sole.

23. In a machine for shaping shoe uppers, wiping means movable in a path substantially parallel to the general plane of a sole to wipe the marginal portion of an upper inwardly over the sole, and a device movable in a path substantially parallel to the path of movement of said wiping means to force an upper-holding fastening inwardly over the marginal portion of the upper, 30 said wiping means having thereon a deflecting face arranged to engage a portion of the fastening as it is thus forced inwardly over the upper and to deflect it into the upper and the sole in a curved path leading reversely outward toward the edge 35 of the sole.

24. In a machine for shaping shoe uppers, means for laying the marginal portion of an upper inwardly over the margin of a sole and against an upstanding lip or shoulder on the sole, 40 a device movable inwardly toward said lip or shoulder to force an upper-holding fastening over the marginal portion of the upper, and means constructed and arranged to engage a portion of said fastening as it is thus forced inwardly over the upper and to deflect it into the upper and the sole in a direction transverse to the direction 45 of inward movement of the fastening.

25. In a machine for shaping shoe uppers, means for laying the marginal portion of an upper 50 inwardly over the margin of a sole and against an upstanding lip or shoulder on the sole, a device movable inwardly toward said lip or shoulder in a path substantially parallel to the general plane of the sole to force an upper-holding fastening over the marginal portion of the upper, 55 and means constructed and arranged to engage a portion of said fastening as it is thus forced inwardly and to deflect it into the upper and the sole in a location nearer the edge of the sole 60 than said lip or shoulder.

26. In a machine for shaping shoe uppers, wiping means for wiping the marginal portion of an upper inwardly over a sole and against an upstanding lip or shoulder on the sole, and a device 65 movable inwardly toward said lip or shoulder in a path substantially parallel to the general plane of the sole to force an upper-holding fastening over the marginal portion of the upper, said wiping means having thereon a deflecting face arranged to engage a portion of the fastening 70 as it is thus forced inwardly and to deflect it into the upper and the sole in a direction transverse to the plane of the sole.

27. In a machine for shaping shoe uppers, 75 means for laying the marginal portion of an up-

per over the margin of a sole around an end of a shoe, means movable inwardly at the opposite side portions of the shoe bottom simultaneously to force into holding relation to the marginal portion of the upper around the end portion of the shoe an upper-holding member having projections thereon, and deflecting means constructed and arranged to engage said projections as said member is forced into upper-holding position and to deflect them into the upper and the sole in 10 directions transverse to the path of movement of said member.

28. In a machine for shaping shoe uppers, means for laying the marginal portion of an upper over the margin of a sole around an end of a shoe, means movable to force into holding relation to the marginal portion of the upper around the end of the shoe an upper-holding member formed to extend around the end of the shoe and having a plurality of projections thereon, and deflecting means constructed and arranged to engage said projections as said member is forced into upper-holding position and to curve them progressively in directions transverse to the plane of the sole to cause them to 25 enter the upper and the sole.

29. In a machine for shaping shoe uppers, means for laying the marginal portion of an upper over the margin of a sole around an end of a shoe, means movable to force inwardly from the 30 edge of the sole over the marginal portion of the upper an upper-holding member formed to extend around the end of the shoe bottom and having a plurality of projections thereon, and deflecting means constructed and arranged to engage said projections as said member is thus forced inwardly and to deflect them into the upper and the sole in curved paths leading reversely 35 outward toward the edge of the sole.

30. In a machine for shaping shoe uppers, overlaying means formed to embrace an end of a shoe and to lay the marginal portion of the shoe upper over the margin of a sole around the end of the shoe, and means movable to force inwardly over the marginal portion of the upper an upper-holding member formed to extend 40 around the end of the shoe and having a plurality of projections thereon, said overlaying means being constructed to engage said projections as said member is thus forced inwardly and to deflect them into the upper and the sole in directions 45 transverse to the plane of the sole.

31. In a machine for shaping shoe uppers, means for embracing an upper around an end of a last and for laying the marginal portion of the upper inwardly over a sole on the last, means movable to force inwardly over the marginal portion of the upper an upper-holding member formed to extend around the end of the shoe bottom and having a plurality of projections thereon, and deflecting means constructed and arranged to engage said projections as said member is thus forced inwardly and to deflect them into the upper and the sole in directions toward 55 the bottom of the last.

32. In a machine for shaping shoe uppers, means for laying the marginal portion of an upper inwardly over the margin of a sole and against an upstanding lip or shoulder on the sole around an end of the shoe bottom, means for forcing inwardly toward said lip or shoulder an upper-holding binder formed to extend around the end of the shoe bottom and having a plurality of projections thereon, and deflecting means constructed and arranged to engage said 60 70 75

projections as said member is thus forced inwardly and to deflect them into the upper and the sole in locations nearer the edge of the sole than said lip or shoulder.

33. In a machine for shaping shoe uppers, wipers formed to embrace an upper around an end of a shoe and movable to lay the marginal portion of the upper upon the margin of a sole, and means movable relatively to said wipers to force into upper-holding position an upper-holding member formed to extend around the end of the shoe and having a plurality of projections thereon, said wipers having portions thereof arranged to lie in the path of said projections for engaging them and deflecting them into the upper and the sole as said upper-holding member is forced into upper-holding position.
34. In a machine for shaping shoe uppers, wipers formed to embrace an upper around an end of a last and movable to wipe the marginal portion of the upper inwardly over the margin of a sole on the last, and members movable relatively to said wipers to force inwardly along the marginal portion of the upper an upper-holding member formed to extend around the end of the shoe bottom and having thereon a plurality of projections arranged to lie substantially in a plane, said wipers having thereon deflecting faces lying in the path of said projections for curving them progressively in directions toward the bottom of the last to cause them to penetrate the upper and the sole as the upper-holding member is forced inwardly over the upper.

35. In a machine for shaping shoe uppers, wipers formed to embrace an upper around an end of a last and movable to wipe the marginal portion of the upper inwardly over the margin of a sole on the last and against an upstanding lip or shoulder on the sole, and members movable relatively to said wipers to force inwardly toward said lip or shoulder an upper-holding binder formed to extend around the end of the shoe bottom and having a plurality of projections thereon, said wipers having thereon deflecting faces arranged to engage said projections as the binder is thus forced inwardly and to deflect them into the upper and the sole toward the bottom of the last in locations nearer the edge of the sole than said lip or shoulder.

36. In a machine for shaping shoe uppers, wipers formed to embrace an upper around an end of a last and movable to wipe the marginal portion of the upper inwardly over a sole on the last, and members movable relatively to said wipers to force inwardly over the marginal portion of the upper in a path substantially parallel to the bottom of the last an upper-holding member formed to extend around the end of the shoe bottom and having a plurality of projections thereon, said wipers having thereon deflecting portions arranged to lie in the path of said projections and so formed as to deflect said projections into the upper and the sole in curved paths leading reversely outwardly toward the edge of the sole as the upper-holding member is forced inwardly over the upper.

37. In a machine for shaping shoe uppers, wipers formed to embrace an upper around an end of a shoe and movable to lay the marginal portion of the upper over the margin of a sole, said wipers having portions thereof spaced from

each other heightwise of the shoe to provide an opening in which to receive an upper-holding member formed to extend around the end of the shoe and having a plurality of projections thereon, and means movable between said different portions of the wipers to force said upper-holding member inwardly over the marginal portion of the upper, said wipers having at their inner edges portions arranged in the plane of said opening for engaging said projections and deflecting them into the upper and the sole as the upper-holding member is forced inwardly over the upper.

38. In a machine for shaping shoe uppers, wipers formed to embrace an upper around an end of a shoe and movable to lay the marginal portion of the upper over the margin of a sole, said wipers having portions thereof spaced from each other heightwise of the shoe to provide an opening in which to receive an upper-holding member formed to extend around the end of the shoe and having a plurality of projections thereon, and members movable between said different portions of the wipers to force said upper-holding member inwardly over the marginal portion of the upper, said wipers having deflecting faces arranged in the plane of said opening and formed to engage said projections and deflect them into the upper and the sole in curved paths as the upper-holding member is forced inwardly over the upper.

39. In a machine for shaping shoe uppers, means for laying the marginal portion of an upper over the margin of a sole around an end of a shoe, binder-applying means movable to force into holding relation to the marginal portion of the upper around the end portion of the shoe an upper-holding binder formed to extend around the end of the shoe and having thereon a plurality of projections arranged to penetrate the shoe at the extreme end thereof and at the sides of its end portion, and deflecting means constructed and arranged to engage said projections and to deflect them into the upper and the sole in directions transverse to the plane of the sole as the binder is thus forced into upper-holding position, said binder-applying means being movable in such relation to the shoe as to cause said projections to enter the shoe first at the extreme end of the shoe and thereafter at the sides of the end portion of the shoe.

40. In a machine for shaping shoe uppers, wipers formed to embrace an upper around an end of a shoe and movable to wipe the marginal portion of the upper inwardly over the margin of a sole, members movable along said wipers to force into holding relation to the marginal portion of the upper a binder formed to extend around the end of the shoe bottom and having thereon a plurality of projections arranged to penetrate the shoe at the extreme end thereof and at the sides of its end portion, said wipers having thereon deflecting faces arranged to engage said projections and deflect them into the upper and the sole in directions transverse to the plane of the sole as the binder is forced into upper-holding position, and means for directing said members in such paths as to cause said projections to enter the shoe first at the extreme end of the shoe and thereafter at the sides of the end portion of the shoe.

FRED N. LA CHAPELLE.
